US00D548362S

(12) **United States Design Patent** (10) **Patent No.:** **US D548,362 S**
Ashby et al. (45) **Date of Patent:** **** Aug. 7, 2007**

(54) **SHED**

(75) Inventors: **Kent Ashby**, Logan, UT (US); **Robert A. Astle**, Farmington, UT (US); **Barry D. Mower**, Layton, UT (US)

(73) Assignee: **Lifetime Products, Inc.**, Clearfield, UT (US)

(**) Term: **14 Years**

(21) Appl. No.: **29/254,653**

(22) Filed: **Feb. 27, 2006**

(51) **LOC (8) Cl.** **25-03**

(52) **U.S. Cl.** **D25/33**

(58) **Field of Classification Search** D25/33, D25/14, 22; 52/79.1, 90.1, 79.5, 64

See application file for complete search history.
